UNITED STATES PATENT OFFICE.

HUGH H. RANJE, OF INDIANAPOLIS, INDIANA.

RAILWAY-TIE.

No. 906,067.

Specification of Letters Patent.

Patented Dec. 8, 1908.

Application filed August 31, 1908. Serial No. 451,075.

To all whom it may concern:

Be it known that I, HUGH H. RANJE, a citizen of the United States, residing at Indianapolis, in the county of Marion and 5 State of Indiana, have invented certain new and useful Improvements in Railway-Ties, of which the following is a specification.

The object of my present invention is to produce an inexpensive, efficient and easily 10 constructed railway tie, as will be hereinafter more particularly described and claimed.

Referring to the accompanying drawings, which are made a part hereof, and on which similar reference characters indicate similar 15 parts, Figure 1 is a view illustrating a railway tie embodying my said invention with railway rails secured thereon, the concrete, however, which forms the body of the tie being broken away for half its length 20 and its position being indicated by means of dotted lines; Fig. 2 a top or plan view of the structure shown in Fig. 1, the rail however being removed at that end where the concrete is absent; Fig. 3 a detail 25 sectional view, on an enlarged scale, illustrating the construction of the metal skeleton portion of the tie more plainly, the section being taken at the point indicated by the dotted line 3 3 in Fig. 4 and Fig. 4 a transverse 30 sectional view at the point indicated by dotted line 4 4 in Fig. 3.

My improved tie consists of a skeleton composed of a longitudinal lower member 21 and an upper cross-shaped rail bearing member 22, the two being connected by struts 23 and 24—the latter being preferably an upturned end of the member 21,—and also by other struts 25 supporting the ends of the arms of the cross, said struts 25 being preferably embodied 40 in a U-shaped structure as best shown in Fig. 4. These parts are firmly united by suitable bolts or rivets as shown. After this skeleton tie is prepared, the same is placed in a suitable mold, and the body 45 of concrete 31 is filled in around it, leaving only the cross-shaped plates 22, which form rail seats, exposed. Previously to placing the skeleton tie in the mold, the bolts 41 are placed therein; and, when the ties are put 50 in position the rails 42 are placed on the metal rail-bearers 22, and are there secured by means of clamps 43 with which the bolts 41 engage, said clamps being drawn down tightly on to the flanges of the rails by means 55 of nuts 44. These clamps are held securely

in place and from turning by means of projections 45 which engage with corresponding openings 46 in the rail-bearers 22.

Having thus fully described my said invention, what I claim as new, and desire to 60 secure by Letters Patent, is:—

1. The combination, in a railway tie, of a metal skeleton composed of a main longitudinal member, rail-bearers, and struts connecting said main longitudinal member and 65 said rail bearers, a body of concrete within which said skeleton is embedded, bolts engaging with said skeleton and projecting upwardly through the rail bearers, and clamps for securing the rail to the tie with which 70 said bolts will engage.

2. The combination, in a railway tie, of a metal skeleton composed of a main longitudinal member, cross-shaped rail-bearers, struts connecting said main longitudinal 75 member and said rail bearers and supporting the four extremities of the latter, a body of concrete within which said skeleton is embedded, bolts engaging with said skeleton and projecting upwardly through the rail 80 bearers, and clamps for securing the rail to the tie with which said bolts will engage.

3. The combination, in a railway tie, of a metal skeleton composed of a main longitudinal member, cross-shaped rail-bearers, 85 struts connecting said main longitudinal member and said rail bearers and supporting the four extremities of the latter, a body of concrete within which said skeleton is embedded, and means whereby the rails are 90 firmly secured upon said rail-bearers.

4. The combination, in a railway tie, of a metal skeleton composed of a main longitudinal member, rail-bearers, struts connecting said main longitudinal member and said 95 rail bearers and supporting the latter, a body of concrete within which said skeleton is embedded, and means whereby the rails are firmly secured upon said rail-bearers, said means and said rail bearers having in- 100 terengaging surfaces.

In witness whereof, I, have hereunto set my hand and seal at Indianapolis, Indiana, this twenty-eighth day of August, A. D. one thousand nine hundred and eight.

HUGH H. RANJE. [L. S.]
